INVENTOR,

Ferdinand Gundorph
By *J. M. Robertson*

Attorney.

UNITED STATES PATENT OFFICE.

FERDINAND GUNDORPH, OF PORTLAND, OREGON.

GRAVITY CLOCK-ESCAPEMENT.

SPECIFICATION forming part of Letters Patent No. 403,999, dated May 28, 1889.

Application filed September 7, 1888. Serial No. 284,811. (No model.)

To all whom it may concern:

Be it known that I, FERDINAND GUNDORPH, a citizen of the United States, residing at Portland, in the county of Multnomah and State 5 of Oregon, have invented a new and useful Clock-Escapement, of which the following is a specification.

The object of my invention is to give impulses of a constant or unvarying power to a 10 clock-pendulum, and at the same time to produce a good electrical contact by each vibration of the pendulum, which I obtain by the following-described construction, illustrated in the accompanying drawings, of which—

15 Figure 1 is a central vertical section. Fig. 2 is a front view. Fig. 3 is a plan of the cross-head B. Fig. 4 is a perspective view of a revolving shaft with arm and weight.

This invention consists in the peculiar combinations, the construction, arrangement, and 20 adaptation of parts, all as more fully herein-after described, and then definitely pointed out in the claims.

In Fig. 1, A A A is a metal bracket screwed 25 onto the clock-ease, intended as a support for the movement, the wheels of which gear into the pinion p, Fig. 1. The lower pivot of this pinion passes down through the bracket, transmitting a revolving motion to the carrier r and arm t. From front to the back, in a 30 line with the pinion, are two slots in the bracket to receive the suspension-springs f f' for the pendulum to hang on.

In Fig. 1, D D is a tubular metal piece, 35 with a metal plug, g, screwed into the lower end, said plug having in its upper end a pivot-rest, x, and its extreme lower end is formed into a connecting-joint, g, for the pendulum-rod k. On the other end of D D is 40 a cross head or bar, B B, (see Fig. 3,) provided on each end with a slot to receive one of the steel springs f and f', before referred to, which are set at right angles to the bar B, said springs having holes in their extreme ends, so 45 that when they are put through the slots in the bracket A A a clamp, W, can be pinned on each, and in this manner secured to the bracket. These suspension-springs form the center of oscillation of the pendulum.

50 At V V' are shown two hard-rubber screws screwed into the bracket, into which are in-

serted two platinum banking-pins, v v', which may be secured there by smaller pins passing through said screws and banking-pins, as shown. To each of these pins is connected in 55 any suitable way a conducting-wire, n n, both of which are to be connected to the negative pole of a battery, and to the positive pole of which is to be connected another wire, o, which is shown connected to the bracket A. 60

Within this frame-like head-piece of the pendulum there is pivoted a small shaft, S, (see Fig. 4,) in line with the axis of the pendulum-rod, with its lower pivot resting on the plug g at x in a jeweled hole. This shaft S 65 has an arm, t, inserted in the shaft at the point of oscillation of the pendulum at a right angle to the shaft S, of an inch long, (more or less,) which can revolve freely in a substantially horizontal plane. On this arm 70 t is placed a small weight, C, from five to ten grains. As this weight is subject to gravitation and only supported by the arm t, having one end resting on the pivot-rest x in the pendulum, the weight C will consequently have a 75 tendency to move the pendulum to one side or bring it out of plumb until the free end of the arm t and weight C have descended about half a degree, when the end of the arm t, projecting through the weight C, will disengage 80 itself by passing below the banking-pin, when the arm t and weight C will be moved round horizontally half a turn by the carrier r, firmly connected with the pivot of pinion p, until the arm t strikes against the other banking-pin, and be arrested there until the weight C has impelled the pendulum to the other side about half a degree, when the arm t will pass under the end of the banking-pin and move round half a turn again until the arm t 85 strikes the banking-pin, Fig. 2, v, and so it will keep on, giving uniform impulses to the pendulum as long as the wheels of the movement turn the pinion p, Fig. 1. If the movement is desired to be used as a circuit-breaker 90 and the wires are connected as above described, the electric current will pass from the bracket A A through the suspension-springs f f', the cross-head B B, the shaft S, the arm t to one of the platinum (or any contact metal) 95 banking-pins, and through the wire n, and the electrical circuit is closed each time the 100

arm *t* strikes a banking-pin. The circuit will be broken when the arm *t* leaves the banking-pin, and in this way an electro-magnet can be operated by each vibration of the pendulum without any irregularity to the impulses given to the pendulum.

Instead of the carrier acting on the arm *t*, it may act on the small pin *E* in the shaft *S*, (see Fig. 4,) which reduces friction on the arm *t*.

It is evident that the weight may be dispensed with if the arm *t* is made heavy enough, as all that is necessary is that said arm shall have sufficient weight to keep up the vibration of the pendulum by its change from one side of the pendulum to the other.

In clock-escapements, even those arranged with constant power, oil is needed, which in course of time will be thick, and the arc of vibration will alter, and consequently the time of its duration. In my escapement oil is not required. It has been in use without oil for a year, and the pendulum swings the same as when first started.

Having thus described my invention, what I claim as new, and desire to secure by Letters Patent, is—

1. In a gravity-escapement and in combination with the pendulum and the motor thereof, a revolving arm deriving motion from the motor, and means, as the pins *v v'*, for intermittently arresting the motion of the said arm, substantially as described.

2. In a gravity-escapement and in combination with the motor and pendulum thereof, a revolving arm connected to the pendulum and driven by the motor, and means, as the pins *v v'*, for intermittently arresting said arm, substantially as described.

3. In a gravity-escapement and in combination with the motor and pendulum thereof, an arm connected to the pendulum and driven by the motor, and means, as the pins *v v'* and wires *n o*, for making and breaking an electrical circuit, substantially as described.

4. In a gravity-escapement and in combination with the pendulum and motor thereof, a revolving arm deriving motion from the motor, and means, as the pins *v v'*, for intermittently arresting the motion of said arm, substantially as described.

5. In a gravity-escapement and in combination with the motor and pendulum thereof, a revolving shaft stepped in the pendulum, an arm mounted on said shaft, a carrier acting on the arm and connected with the motor, and means, as the pins *v v'*, for intermittently arresting said arm, substantially as described.

6. In a gravity-escapement and in combination with the motor and pendulum thereof, a pinion, *p*, meshing with the motor, a shaft driven by said pinion, a carrier revolved by said shaft, a revolving arm, *t*, connected with the pendulum and revolved by the carrier, and means, as the pins *v v'*, for intermittently arresting said arm, substantially as described.

7. In a gravity-escapement and in combination with the motor thereof, a pendulum having a tube at its upper end, a shaft revolving in said tube, an arm attached to said shaft, a carrier connecting said arm with the motor, and means, as the pins *v v'*, for intermittently arresting the motion of the arm and shaft, substantially as described.

8. In a gravity-escapement and in combination with the motor thereof, a pendulum having a tube at its upper end, a shaft carrying an arm and revolving in said tube, a pivot-rest supporting said shaft, a carrier connected with the motor and driving the shaft, and the pins *v v'*, for intermittently arresting said revolving arm and shaft, substantially as described.

9. In a gravity-escapement and in combination with the motor thereof, a vertical shaft connected with the motor, a carrier connected with said shaft, a cross-head, *B*, having suspension-springs *f*, connected to a suitable support, a tube, *D*, beneath the cross-head, a revolving shaft, *S*, working in said tube, an arm, *t*, carried by said shaft, a weight, *C*, adjustable on said arm, the pins *v v'*, for arresting the motion of the arm, and the pendulum-rod *k*, connected to the bottom of the tube, substantially as described.

FERDINAND GUNDORPH.
